[57] CLAIM

The ornamental design for a hood portion of a tractor vehicle, substantially as shown and described.

DESCRIPTION

FIG. 1 is a perspective view of a hood portion of a tractor vehicle seen from the right front of the vehicle showing our new design;

FIG. 2 is a front elevation view thereof;

FIG. 3 is a right side elevation view thereof; and

FIG. 4 is a top plan view thereof.

The side opposite to that shown in the drawing is substantially a mirror image thereof.

The dotted lines depicting a tractor are for illustrative purposes only.
